(57) **CLAIM**

(21) Appl. No.: **29/313,499**

The ornamental design for a rocking chair with a cantilever seat and a flexible back structure, as shown and described.

(22) Filed: **Jan. 13, 2009**

DESCRIPTION

(51) **LOC (9) Cl.** **06-01**

FIG. 1 is a front perspective view of a rocking chair with a cantilever seat and a flexible back structure showing my new design;

(52) **U.S. Cl.** **D6/348**

FIG. 2 is a side elevation view showing the rocking chair, the opposite side being a mirror image thereof;

(58) **Field of Classification Search** D6/334–336,

FIG. 3 is a top plan view thereof; and,

D6/348, 360–369, 370–375, 379–381, 498,

FIG. 4 is a rear elevation view thereof.

D6/500–502; 297/3, 68, 284.4, 344.19, 423.1,

The portions of the article not shown in the drawing or
described in the specification form no part of the claimed
design.

297/423.19, 440.13, 452.12, 452.17, 452.21,

297/452.29, 452.3, 452.56, 452.64

See application file for complete search history.
